UNITED STATES PATENT OFFICE.

SIMON W. WARDWELL, OF PROVIDENCE, RHODE ISLAND.

TAKE-UP AND WINDING-ON MECHANISM FOR BRAIDING-MACHINES.

1,083,642.

Specification of Letters Patent.

Patented Jan. 6, 1914.

Application filed May 22, 1911. Serial No. 628,816.

To all whom it may concern:

Be it known that I, SIMON W. WARDWELL, a citizen of the United States, residing at Providence, in the county of Providence and State of Rhode Island, have invented 5 certain new and useful Improvements in Take-Up and Winding-On Mechanism for Braiding-Machines, of which the following is a specification.

10 My invention relates to improvements in braiding machines and particularly to the mechanism for holding the take-up reel and winding the product of the machine thereon.

The object of my improvement is to provide means to facilitate the operation of applying the take-up reel to the machine and removing the reel from the machine after it has been filled; and to also provide for winding the product of the machine on the 20 reel in regularly laid, systematically wound coils so that the material will be closely compacted in commercial form in condition to be unwound without snarling or tangling.

The invention is fully described in the 25 following specification, illustrated by the accompanying drawings, in which:

Figure 1 is a front elevation of a braiding machine showing my invention applied thereto; Fig. 2, an enlarged front view of 30 the devices for holding and driving the take-up or winding-on reel; Fig. 3, a side elevation of the supporting devices for one side of the reel; Fig. 4, an enlarged detail view of the reel-driving mechanism; Fig. 5, an 35 enlarged front view of the take-up and winding mechanism for guiding the braid as it leads to the reel; Fig. 6, a side elevation of the same; Figs. 7, 8, 9 and 10, detail views of the mechanism therefor.

40 In Fig. 1 I have shown a rotary braiding machine, designated B, mounted on the table or standard T and driven from a shaft o having a pulley p belted to a pulley p' on the line shaft P. Mounted on an arbor s extending between the legs t, t' of the table T is the supply reel S from which is delivered the wire w or other material over which the fabric is to be braided. The wire w, or other core for the braid, is led up through 45 the center of the machine and covered by the tubular fabric b braided from the yarns y, y, etc. As the braid is fabricated about its core w the product is taken up by a take-up wheel W adapted to feed the core 50 through the machine. As the material b leaves the braiding point x it is given one or more turns around the wheel W and then leads to a guide-arm A and is thence delivered to the winding-on reel R and coiled regularly thereon. The reel R is preferably 60 supported between the legs of two adjacent tables T and T', it being the usual practice to set the braiding machines in rows with a slight space between each two. The novel means for supporting and driving the take-up or winding-on reel will now be described in detail.

Referring to Fig. 2, a stud shaft 2 is journaled in the bearing 3 of a bracket 4 fastened to a cross-arm 5 of the leg t', and serves as an arbor for one side of the reel R. The shaft 2 carries an arm 6 on one side of the bearing 3 and at its end is a stud 7 adapted to engage a hole 8 in the flange r of the reel R, whereby the reel is driven 75 through the rotation of the shaft. The shaft 2 is rotated through a pinion 9 and gear 10, the latter being connected to the shaft by a friction-clutch device as now described: Fast on the shaft 2 is a clutch-disk 80 11 formed with an annular flange 12 on which is mounted the gear 10, constructed as a ring. A second disk 13 is axially mounted on a stud 14 screwed into the outer end of the shaft 2. The stud 14 has a hand 85 nut 15 at its outer end, and bearing against the inner face thereof is a spider spring 16. The ends of the prongs 17 of the spring 16 bear against the side of the disk 13 to force the latter against the face of the gear-ring 90 10, and the gear, in turn, is forced against the face 18 of the disk 11. By turning the stud 14 the pressure of the spring 16 can be 95 adjusted to regulate the frictional contact of the disks 11 and 13 against the sides of 105 the gear-ring 10. The pinion 9 rotates on a stud 19 secured in an arm 20 of the bracket 4, see Fig. 4, and carries a sprocket wheel 21 rotatable therewith. The sprocket 21 is connected by a chain 22, see Fig. 1, to be 110 driven from the drive-shaft o of the machine in any suitable manner, not here shown in detail. On the leg t of the next adjacent table T', see Figs. 1 and 2, is hinged a swinging arm 23 which carries at its lower end an arbor or bearing 24 for the opposite side of 115 the reel R. Preferably the arbor 24 is formed as a flanged bushing mounted rotatably on the stud 25 driven into a boss on the arm. Referring to Figs. 2 and 3, the upper end of the arm 23 is formed with two laterally projecting studs or trunnions 26,

26 which are seated in socket bearings 27, 27 formed in the downwardly projecting arms 28, 28 of the bracket 29. The bracket 29 is secured to the upper cross-arm 30 of the table T'. Adjacent the lower end of the arm 28 is a laterally projecting lug 31 formed with a slot 32. Mounted in a bearing 33 on the leg t is a rod 34 formed with a crank-arm 35, the extremity of which engages the slot 32. The opposite end of the rod 34 is bent to form a handle 36 and by turning the latter the arm 28 can be swung on its bearings to engage and disengage the arbor 24 with the bore of the reel R.

Referring to Fig. 2, after one side of the reel has been mounted on the arbor shaft 2 the crank handle 36 is turned downwardly and the crank-arm 35 acts to swing the arm 28 into the position illustrated by full lines 26 to engage the arbor 24 with the bore of the reel. The end of the handle 36 engages the side of an ear 37 on the leg t, see Figs. 1 and 3, to limit the turning movement of the rod 34 in this direction, and preferably when the handle 36 is thus engaged the crank-arm 35 is slightly below the center of the rod 34. Through this arrangement the arm 28 is locked against swinging out and away from the reel, and any jar or vibration of the arm 30 cannot act to lift the crank-arm 35 since it is below center. To free the arbor 24 from the reel, to allow the removal of the latter, it is only necessary to turn the handle 36 upwardly and the crank-arm 35 then acts to swing the arm 28 into the position illustrated by dash lines in Fig. 2. The turning movement of the rod 34 in this direction is limited by a pin 39 driven into the bearing 33, see Fig. 3, and adapted to be engaged by the crank-arm 35.

The grooved take-up wheel W which feeds the wire w through the machine and takes up the braided material b rotates on a fixed shaft 40 held in the standards k, k which are mounted on the table T. Formed on the periphery of the wheel W is a gear g meshing with a pinion h which rotates with the shaft f. The shaft f is driven from the drive shaft o of the machine through gear and chain connections not here shown or described in detail as they form no part of the present invention.

Mounted on the shaft 40, see Figs. 6, 7 and 8, is a bracket 41 having a bifurcated portion 42, 42 bored to receive the shaft and arranged to straddle the bearing 43 at the top of the standard k. An arm or tail-piece 44 extends downwardly from the bracket 41 with its end bearing against the side of the standard k to support the weight of the bracket and the devices carried thereon. To prevent upward movement of the bracket 41 a set screw 45 is screwed through one of the ears 42 with its end abutting the rib 46 of the arm k, see Figs. 6 and 7. The bracket

41 is formed with an upwardly extending arm 47 terminating in the bearing 48 in which is secured a rod 49, held by the set screw 50. Mounted on the rod 49 and held in position by a spring-pin 51, see Fig. 5, is the rocking guide-arm A which receives the braided material b as it leads from the take-up wheel W and delivers it through the depending guide 52 to the winding-on reel R. The arm A is formed with a curved, sickle-shaped rim 53 supported eccentrically to the hub 54 by the arms or spokes 55. The rim 53 has a flange 56 on one of its sides, see Fig. 6, and on the opposite side is secured a plurality of disks or washers 57, held by rivets 80 or other suitable means. The material b leads over the curved rim 53 and is held thereon between the flange 56 and disks 57. Depending from the lower end of the rim 53 is the guide 52, preferably formed of wire bent into a goose-neck at 58, see Fig. 6, which forms the guide-eye for the material. The ends of the wire are held in bores in the lugs 59, 59 on the arm A and the length of the guide 52 can be adjusted by sliding the wire through the lugs. Suitable means such as the set screws 88, 88 are provided, see Fig. 6, to bind the ends of the wire in these bores to retain the guide in its adjusted position. The guide-arm A is rocked on its bearing to traverse the guide-eye 58 back and forth across the barrel of the reel R to lay the material on the reel in regularly disposed coils as shown in Fig. 1. The full lines illustrate the position of the guide at one extreme of its traverse and the dash lines show the guide at the opposite extreme. By shortening or lengthening the guide-wire 52 as above described the extent of traverse of the guide-eye 58 can be varied to adapt the winding to different widths of reels.

For oscillating the arm A any suitable means might be employed but I prefer to make use of a heart-shaped cam operated and arranged as follows: Referring to Figs. 5, 6, 7 and 8, a stud 60 projects from the bearing 61 of the bracket 41, being held in its bore by a set screw 62. Mounted rotatably at the end of the stud 60 is a toothed wheel or ratchet 63 which has attached thereto, or formed integral therewith, the heart cam 64, see Figs. 9 and 10. The wheel 63 and its cam 64 are held in position longitudinally of the stud 60 by a novel device which also applies a slight frictional resistance to their rotation, to prevent the ratchet-wheel from slipping back or running ahead when operated by the pawl mechanism later described. This consists of a wire spring clip 65 having a straight portion 66 held in a transverse hole at the end of the stud 60, and a circular extension 67 adapted to be sprung into an annular groove 68 formed on the interior of the rim 69 of the cam 64. Located between the hub 71 and

of the wheel 63 and the end of the bearing 61 is lever 70 adapted to rock on the stud 60, see Figs. 7 and 8. The lever 70 carries a pawl 72 pivoted at 73 and formed with 5 the depending weighted arm 74. The pointed end of the pawl 72 engages the notches or teeth 75 on the periphery of the wheel 63 with the weight 74 swinging inside the wheel to effect said engagement. To prevent the weighted arm of the pawl from swinging up too far, from accident or other cause, a lug 76 is provided on the lever 70 to limit such upward movement. The ratchet-wheel 63 is turned in the direction indicated by the arrow, Fig. 7, through the upward lift of the lever 70, and movement of the lever is effected through engagement therewith of a stud or pin 77 on the take-up wheel W. Preferably the stud 77 is 20 screwed through one of the spokes 78 of the wheel W to adapt it to be adjusted in relation to the end of the lever 70 and a check nut 79 is provided to lock the stud in its adjusted position.

25 It will be observed that when the stud 78 is set to engage the lever throughout only a relatively slight distance the upward movement of the stud will move the lever but a short distance before the end of the stud 80 slides off the end of the lever. When a greater movement of the lever 70 is desired the stud 77 is screwed farther through the spoke 78 to provide for a longer engagement between the two, and consequently the lever 85 70 is given a greater lift and the pawl 72 thereby turns the wheel 63 through a longer arc. I also provide another adjustment for the lever 70 in the set-screw 80 projecting through the lug 81 on its hub and adapted 40 to be locked by the check-nut 82. The end of the set-screw 80 is adapted to contact with the rib 83 on the bracket 41 to limit the downward movement of the lever 70 and by adjusting this screw the position of the 45 lever in relation to the stud 77 is changed so that the timing of engagement between the two can be regulated to vary the movement of the lever as before described. The cam 64 acts through a roll 85 pivoted on the lug 50 86 of the arm A and engaging its periphery to rock the arm alternately up and down with a motion similar to that of a walking-beam, this movement causing the traverse of the guide 55 58 as before described.

55 The operation of the whole apparatus is as follows: The supply reel S is mounted on its arbor 2 and the wire w led up through the machine and given several turns around the take-up wheel W. The empty winding-on 60 reel R is mounted at one side of the machine by inserting the end of the arbor 2 in its bore and entering the stud 7 in the hole 8 of its flange r. The arm 23 is then swung into position to bring the arbor 24 into the 65 bore on the opposite side of the reel by turn-

ing the handle 36, as before described. As the braid is fabricated about the wire the finished material b is fed from the machine by the wheel W and is led over the rim 53 of the arm A. The arrangement of the washers 57 on the front of the rim 53 provides for convenience in placing the material on the rim, as it is only required to slip it behind each washer in turn; and in addition the braid is practically always in full view from the front of the machine so that it can be inspected by the operator from time to time. From the rim 53 the material is led down through the guide 58 and its end fastened to the barrel r of the reel R. When different widths of reels are used the guide-eye 58 is adjusted in relation to the arm A, as before described, and in this way the traverse or throw of the guide can be regulated as required.

When the machine is operating the pinion 9 will be driven from the shaft o and the gear 10 is rotated thereby. The ratio of the gearing between the shaft o and gear 10 is such as to ordinarily drive the reel R at a speed a trifle in excess of what is required to wind the material on the barrel of the reel. The rate of feed of the product of the machine is, of course, constant and as the material builds up on the barrel in layers the speed of the reel must decrease with the increasing diameter of the winding. In other words, when the winding is being performed on the minimum diameter the reel must be rotated with greater speed to take up the material than when the material is winding on a relatively large diameter. To provide for this gradual reduction in the speed from start to finish of the winding the clutch-device on the arbor shaft 2 is arranged to rotate the shaft and arm 6 with an inductive drive so that the speed of the reel will be accommodated to the rate of delivery of the material. To effect this the spring 18 is adjusted to give just enough friction between the disk 11 and gear 10 to keep the material under tension while allowing a constant slippage between the two as the rotation of the reel is gradually retarded with the increase in diameter of the winding.

The take-up wheel W is driven at the speed required for the particular character of fabric being braided and at each rotation of the wheel the stud 77 on its spoke 78 will engage the end of the lever 70 and lift the latter to carry the pawl 72 through a short arcal movement. The end of the pawl is maintained in engagement with the teeth 75 on the periphery of the wheel 63 by the weight 74 and through this engagement the cam 64 is rotated in the direction indicated by the arrow in Fig. 7. As the stud 77 rides upward with the turning of the wheel W it slides off the end of the lever 70 and the latter drops back under the influence of gravity.

4
into position to be engaged again at the next revolution of the stud. In this way the ratchet-wheel 63 and its cam 64 are rotated intermittently from the rotation of the wheel W but at a much slower speed. As the pawl 72 rides back on the periphery of the wheel 63 there will be a slight friction between the two, tending to rotate the wheel backward, but this is prevented by the friction of the spring-clip 65 which holds the wheel until it is positively moved forward again.

The rotation of the cam 64 causes the stud or roll 85 to travel over the peripheral face 15 of the cam from the low point to the high point and back again to the low point. This causes the roll 85 to rise and fall to oscillate the arm A with a rocking motion and the guide 58 is traversed back and forth 20 across the barrel of the reel R as illustrated in Fig. 1. By adjusting the stud 77 in the spoke 78 and the set-screw 80 in the arm 81 of the lever 70 the length of engagement, between the stud and lever can be regulated, 25 as before described, to give a greater or less movement of rotation to the wheel 63 and cam 64. In this way the oscillation of the arm A and the traverse of the guide 58 is timed to wind the material on the reel R in 30 close wound coils laid regularly, side by side. As the layers of coils build up on the reel the ratio between the traverse of the guide and the turning of the reel will vary a little, owing to the retardation of the 35 speed of the latter; but the effect of this is merely to wind the coils a trifle farther apart or more open and this slight change in the wind is not material.

Heretofore in braiding machines the usual 40 practice has been to simply rotate the take-up reel and let the material wind thereon indiscriminately without controlling the laying of the coils. This method of taking up the product of the machine is very unsatisfactory for several reasons: The material 45 when uncontrolled will wind up in a haphazard manner with a heterogeneous mass of coils crossing and recrossing each other and so confused as to prevent free delivery 50 in unwinding. In some cases where the coils build up in a relatively narrow mound, the outer coils will slip off and become loose and subsequent coils laid across these will chafe, bind and crimp the material and 55 damage the fabric to such an extent as to render it unfit for use. Frequently the material will be in such a tangled state that the reel must be unwound very carefully by hand and the product rewound to render it 60 capable of delivering in applying it to the coating or other processes of manufacture. My improved winding device obviates all 65 these difficulties now encountered and provides for putting the material into such form as to compact a maximum quantity on

the reel in condition to be freely delivered therefrom, either for other processes of manufacture or as a commercial package. Furthermore, the whole arrangement of the apparatus provides for the most convenient 70 and economical operation of the braiding machine and the handling of its product, so that the capacity of the machine is increased and its product improved.

Various modifications might be made in 75 the structure and arrangement of the parts of my device without departing from the spirit and scope of the invention.

Therefore, without limiting myself to the exact construction shown, what I claim is: 80

1. In a braiding machine, the combination with the braiding mechanism, of a take-up reel, means to guide the material from the braiding mechanism to the reel, comprising an arm A formed with a curved rim 85 over which the material leads, said rim having a flange 56 along one side, and members 57 secured at intervals along the other side of the rim, adapted to cooperate with the flange to maintain the material on the rim. 90

2. In a braiding machine, the combination with the braiding mechanism, of a rockable arm pivoted above the machine and formed with a curved rim arranged eccentrically with the pivot of the arm and adapted to receive the material as it leads from the braiding mechanism, a guide for the material extending from said arm, means to adjust the guide in relation to the pivot of the arm, and means to rock said arm to 100 traverse the guide.

3. In a braiding machine, the combination with the braiding mechanism, of a rockable arm, a guide on said arm adapted to receive the material as it delivers from the braiding mechanism, a cam, means on the arm engaging the cam, a ratchet-wheel to rotate the cam, a lever, a pawl mounted on said lever to engage the ratchet-wheel, and means to intermittently move the lever to turn 110 the ratchet-wheel.

4. In a braiding machine, the combination with the braiding mechanism, of a take-up wheel to feed the material from the braiding mechanism, a rockable arm, a guide on said arm adapted to receive the material as it delivers from the take-up wheel, a cam to rock the arm, a ratchet-wheel to turn the cam, a pawl to turn the ratchet-wheel and means on the take-up wheel adapted to 120 actuate the pawl.

5. In a braiding machine, the combination with the braiding mechanism, of a take-up wheel to feed the material from the braiding mechanism, a rockable arm, a guide on 125 said arm adapted to guide the delivering material, a cam to rock said arm, a ratchet-wheel to rotate the cam, a lever, a pawl on said lever adapted to engage the ratchet-wheel, and means adjustable on the take-up 130

wheel to intermittently operate the lever to rotate the ratchet wheel.

6. In a braiding machine, the combination with the braiding mechanism, of a take-up wheel to feed the material from the braiding mechanism, a rockable arm, a guide on said arm adapted to guide the delivering material, a cam to rock the arm, a ratchet-wheel to rotate the cam, a lever, a pawl on said lever arranged to engage the ratchet-wheel, and means on the take-up wheel acting to engage and actuate the lever at each rotation of the wheel, said means adjustable to vary the extent of such engagement to regulate the range of movement of the lever.

7. In a braiding machine, the combination with the braiding mechanism, of a take-up wheel to feed the material from the braiding mechanism, a rockable arm, a guide on said arm adapted to guide the delivering material, a cam to rock the arm, a ratchet-wheel to rotate the cam, a lever, a pawl on said lever adapted to engage the ratchet-wheel, means on the take-up wheel to engage and actuate the lever, and means to adjust the lever in relation to the engaging means therefor to vary the extent of engagement and regulate the range of movement of the lever.

8. In a winding mechanism for braiding machines, the combination of a rockable arm, a guide on said arm adapted to guide the material delivering from the machine, a fixed shaft, a cam rotatable on said shaft and arranged to rock the arm, a ratchet-wheel to rotate said cam, a pawl to rotate the ratchet-wheel, and a spring-clip secured

in the shaft and frictionally engaging the cam to prevent backward rotation of the latter under influence of the backward movement of the pawl on the ratchet-wheel.

9. In a winding mechanism for braiding machines, the combination of a rockable arm, a guide on said arm adapted to guide the material delivering from the machine, a fixed shaft 60, a cam rotatable on said shaft and arranged to rock the arm, a ratchet-wheel 63 on the shaft 60 formed with a rim 69, a wire clip 65 having a portion 66 engaging a transverse hole in the shaft and a circular extension 67 engaging the inside of the rim 69 to provide frictional resistance to the rotation of the wheel, and a pawl to rotate the ratchet-wheel.

10. In a winding mechanism for braiding machines, the combination of a rockable arm, a guide on said arm adapted to guide the material delivering from the machine, a fixed shaft 60, a cam rotatable on said shaft and arranged to rock the arm, a ratchet-wheel 63 on the shaft 60, said ratchet-wheel having a rim formed with an annular groove, a spring member secured to the shaft 60 and having a circular portion sprung into the groove to retain the wheel axially of the shaft and apply resistance to its rotation on the shaft, and a pawl to rotate the ratchet-wheel.

In testimony whereof I affix my signature in presence of two witnesses.

SIMON W. WARDWELL.
